COMBINATION PILOT AND VAPORIZING
DEVICE FOR HORIZONTAL POT TYPE
BURNERS

Edward H. Stempel and Marcus L. Nelson, Albert Lea, Minn., assignors to American Gas Machine Company, Albert Lea, Minn., a corporation of Minnesota

Application October 15, 1945, Serial No. 622,258

4 Claims. (Cl. 158—91)

1

This invention relates to liquid fuel burners of the so-called "pot" type and particularly, to a combination pilot and vaporizing device for such burners.

It is an object of our present invention to provide a simplified and highly efficient combination pilot and vaporizing device particularly adapted, but not restricted to horizontal pot type oil burners.

Another object is the provision of a combination pilot and vaporizing device of the class described, wherein a highly efficient admixture and combustion of fuel and air is obtained on pilot flame and on a variety of different flame settings.

It is a further object to provide a combination pilot and vaporizing device for pot type burners which will cause a vaporized mixture, during heating operation of the burner, to be discharged within the pot circumferentially therein, whereby a very efficient secondary mixture of additional air is effected before combustion takes place.

A further and more specific object is the provision of a simplified device of the class described wherein a portion of the peripheral wall of the burner pot in itself constitutes the air admission means and a wall of the pilot housing, the remainder of the pilot and vaporizing structure being formed by a shell or receptacle mounted against a portion of said peripheral wall.

These and other objects and advantages of our invention will be more apparent from the following description made in connection with the accompanying drawings, wherein like reference characters refer to the same parts throughout the several views and in which:

Fig. 1 is a vertical section taken axially through an embodiment of our invention, applied to such a device as a floor furnace;

Fig. 2 is a cross section taken on the line 2—2 of Fig. 1, showing the burner pot with our pilot and vaporizing device applied thereto in end elevation;

Fig. 3 is a vertical cross section taken on the line 3—3 of Fig. 1;

Fig. 4 is a view similar to Fig. 1 showing, however, another form of our invention; and

Fig. 5 is a cross section taken on the line 5—5 of Fig. 4.

Referring now to the form of the invention illustrated in Figs. 1 to 3 inclusive, our combination pilot and vaporizing device is incorporated in a horizontal pot type oil burner associated with the interior of a heating device such as a floor furnace. The floor furnace includes the

2

main combustion chamber C having mounted within one end thereof, a horizontally disposed cylindrical casing 11 constructed of suitable material such as sheet metal, which, as shown, extends inwardly at one end past the vertical partition 12 defining one wall of the combustion chamber and which at its opposite end is abutted against a vertical wall 13 constituting, in the floor furnace illustrated, the exterior wall thereof.

It will, of course, be understood that any suitable means may be utilized for securing the casing 11 to the body of the heater or furnace. As shown, we provide the casing 11 with an intermediate disposed, outwardly pressed bead 11a by which the casing is clamped in a circular aperture formed in partition 12 and is mainly supported by said partition and the bottom 12b of the combustion chamber. To facilitate such mounting and clamping action the apertured casing-receiving portion of partition 12 is preferably provided with a turned flange 12a adapted to be engaged at its outer edge against the casing bead 11a, and a clamping ring 14 of angle iron construction surrounds casing 11 and is clamped by bolts 15 against the bead 11a threadedly secured to the partition 12. As shown, at the bottom of the casing, we utilize a reinforcing channel member 50 to support the lower part of casing 11.

Casing 11 has concentrically mounted thereon, a horizontal pot type burner comprising a circumferential or peripheral wall 16 preferably constructed of suitable sheet metal and spaced a short distance within cylindrical casing 11 to provide an annular air chamber surrounding the burner. The peripheral wall, as is common in burners of this type, is provided with a multiplicity of spaced air admission ports or apertures 16a which as shown, are arranged in alternately staggered circumferential rows. The rear end of the pot burner is preferably but not necessarily closed by a circular vertical wall 17 as shown, having an outturned flange that telescopes within the outer end of burner casing 16 and may be removably secured thereto by one or more bolts or screws 17a.

At the inner or forward end of the pot burner, a flame ring 18 is provided of considerably smaller internal diameter than that of the casing or peripheral wall 16 and as shown, secured to a flanged ring and closure member 19, the outturned flange of which is telescoped within the forward end of cylindrical casing 11 and welded or otherwise fixed thereto, the body of which extends between the inner periphery of casing 11 and the mar-

ginal edge of flame ring 18 to close the annular air chamber defined between the pot burner and the casing 11 and to further constitute a supporting means for the flame ring and the casing 16 of the burner. A secondary air admission ring 20 is secured at its inner marginal portion to closure member 19 and to flame ring 18 as by threaded bolts 18a and has a rearwardly turned attachment flange 20a which as shown, is telescoped over the forward annular edge of the circumferential wall 16 of the burner and welded or otherwise rigidly secured thereto. The ring 20 in the body or vertical portion thereof, is provided with one or more series of secondary air admission ports 20b which extend longitudinally of the pot burner and are associated with a deflector lip 21 of ring shape disposed parallel to the ring 20 and inwardly of the same in spaced relation and welded or otherwise affixed by an outturned attachment flange 21a to the interior of the forward end of peripheral wall 16.

Our combination pilot and vaporizing device is mounted in the upper and rearward portion of the horizontal burner illustrated in Figures 1 to 3, and in general comprises a substantially closed casing provided with a bottom for reception of liquid fuel and a top provided with a multiplicity of air inlet ports or apertures adapted to direct jets of air downwardly against the vaporizing fuel. As shown the top of said casing is formed by a section or portion 16x of the peripheral wall of the pot burner having a multiplicity of air intake passages 16b formed therethrough and preferably, but not necessarily, being of smaller diameter and more numerous and in closer spaced relationship than the other air intake passages formed in other portions of the circumferential wall 16. The remainder of the pilot and vaporizing casing is formed by a receptacle shell horizontally disposed in the upper portion of the pot and having upwardly diverging side walls 22a, vertical end walls 22b, and a bottom 22c. The end walls 22b are arcuately and convexly shaped at their upper edges to conform to the cylindrical inner periphery of pot 16 and are secured flush against the upper portion of the pot casing by suitable means such as angled retaining flanges 22d which may be integrally formed from the end walls or may be in the form of angle irons welded or otherwise secured thereto. The casing adjacent the top of the burner is provided with longitudinal passages 23 extending in the form now described throughout the length of the side walls 22a and conveniently formed by constructing the side walls short of engagement with the top of the casing formed by the section 16x of the circumferential wall 16 of the pot. Thus in this form of the invention, discharge of vapors and gases from within the pilot and vaporizing casing takes place through the longitudinal passages 23 extending substantially the full length of the casing, and directing such vapors and gases laterally and in opposite directions from the casing and circumferentially of the burner pot in close relation to the inner peripheral wall of the pot.

Provision for lighting the pilot burner is suitably made as by an aperture in the section 16x of the circumferential wall 16 of the pot provided with an upstanding neck 24 which extends through the outer cylindrical casing 11 and as is shown, is closed by plug or cap 24a associated therewith.

A fuel conduit 25 extends through the exterior wall of the heating device and within cy-

lindrical casing 11 and communicates with the interior of the lower portion of the casing adjacent preferably the rear or outer end thereof, a suitable fitting 25a being provided, as shown, for threaded connection with the extremity of conduit 25. An automatic, adjustable, constant level or constant flow valve 27 of conventional type is illustrated as interposed in the fuel supply conduit 25 exteriorly of the burner and heating device to which the burner is applied, this valve being of any suitable well known type adapted to be set in a plurality of positions to maintain flow or level of fuel within the vaporizer and pilot housing at a pilot setting and various low and high flame settings.

As shown, the exterior wall of the furnace or heating device 13 is provided with a removable plate 13a disposed substantially centrally of cylindrical casing 11 and provided with a relatively large air intake aperture 13b. In many installations, a booster fan 28 is utilized with our structure and may be conveniently mounted on plate 13a for setting up a draft of air inwardly through the annular air passage defined between cylindrical casing 11 and burner casing 16. It will of course, be understood that in many installations, a booster fan is not required or desirable.

In operation with the flow or constant level valve 27 adjusted for pilot setting, oil or other liquid fuel is delivered to the bottom 22c of the pilot and vaporizing receptacle maintaining a substantially constant level for pilot purposes. The ignition of the fuel is effected by dropping a fragment of burning paper or the like through the lighting neck 24 into the vaporizing casing. Air is then supplied through the multiplicity of air admission ports 16b in the top of the vaporizing casing provided by the section of the burner wall 16x to hydroxylize the vaporized fuel in quantities very nearly sufficient for pilot combustion. The air is directed downwardly through ports 16b in the top of the vaporizing casing, in the form of jets against the upwardly rising fuel vapors and the mixture burns as it discharges from the longitudinal upper passages 23 through the side-walls of the pilot and vaporizing casing where secondary air is admitted to the mixture through air supplied to the burner casing from the multiplicity of spaced radial main air ports 16a.

Thus, a very complete combustion of a relatively small amount of fuel vaporized at pilot setting, is obtained in the upper portion of the horizontal burner, the flames discharging from the pilot casing laterally thereof, in opposite directions and circumferentially outward and downward and serving to very efficiently and uniformly heat the interior of the pot burner.

When the valve 27 is adjusted to maintain the fuel level within the receptacle of the vaporizing housing at a level above pilot setting, the air admitted to the vaporizing casing through the ports 16b in the top thereof, is inadequate to support combustion but is directed downwardly in jets very efficiently admixing with the upwardly rising vapors and producing a hydroxylized admixture which discharges as indicated by the arrows in Fig. 3 laterally from the vaporizing casing in opposite directions, circumferentially of the horizontal burner pot and guided by the peripheral wall 16 of the pot outwardly and downwardly. This mixture is efficiently supplied with additional air furnished to the interior of the pot burner through the multiplicity of primary air ports 16a and at the lower flame settings above pilot setting, will burn at least partially within

the burner casing with what is known as a low flame.

At high flame setting with the level of liquid fuel in the vaporizing casing disposed some distance above the bottom 22c, the primary air supply furnished by the multiplicity of ports 16b in the top of the vaporizing casing, with the relatively large additional primary air supply furnished by the main primary air ports 16a in the circumferential wall 16 of the burner, is not adequate to support combustion within the interior of the burner. Secondary supply of air is furnished at the inner or open end of the burner through the multiplicity of ports 20b in air supply ring 20 and this air is directed inwardly towards the axial portion of the interior of the burner by means of the deflection ring 21, very efficiently mixing with the hydroxylized mixture and producing combustion outwardly of the flame ring 18.

With most horizontal pot type burner constructions, it has been difficult to obtain adequate temperatures in the upper portion of the burner pot for producing efficient combustion and proper mixture of the vaporized fuel and combustion-supporting air. With our improved structure the pilot burning and low flame burnings of the device produce adequate temperatures within the upper portion of the horizontal burner and materially improve combustion efficiency and elimination of carbon in the upper portion of the burner. Furthermore, this construction provides for a very efficient circulation and admixture of the hydroxylized fuel from the vaporizing casing in heating operation of the burner with the primary and secondary main air supplies.

In most vaporizing and pilot constructions for horizontal burners, the vaporized fuel has been discharged from the axial or core portion of the burner casing rather than from the upper portion thereof and has not been distributed circumferentially within the inner periphery of the cylindrical burner wall. We have obtained improved results in mixture of the vaporized fuel with the air supply and in proper heating of the entire interior of the burner casing with our improved structure.

In Figs. 4 and 5, a somewhat different form of our invention is illustrated associated with a pot type burner and heating device or floor furnace, both of similar construction to the form previously described. The parts of the heating device and pot type burner are accordingly, numbered similarly to the form illustrated in Figs. 1 to 3 inclusive.

In this second form of our combination pilot and vaporizing device, we provide a casing generally similar to the form first described and having its top covering formed by a section 16x at the top and rear portion of the circumferential wall 16 of the pot burner. The casing has a bottom 22c and end walls 22b similar to the casing of the form first described, the end walls at their upper edges being shaped to conform to the circumference of the section 16x of the burner wall and secured thereto as in the form first described.

The interior of the pilot and vaporizing casing is divided into two compartments A and B by a substantially central, vertical partition 29, said partition being provided with a relatively large, inverted, U-shaped communicating aperture 29a which extends some distance above the "high" fuel level of the receptacle portion of the casing. The side walls 22a of the casing are extended upwardly into abutment or substantial registration with the section 16x of the circumferential wall

of the burner throughout their portions between the rear end of the burner and vertical partition 29 of the casing, whereas at their forward, upper longitudinal edges, the upwardly diverging walls terminate in parallel, spaced relation to the top of the burner wall defining longitudinal discharge passages 30 as clearly shown in Fig. 5.

In this form of the invention, a multiplicity of primary air inlet ports or apertures disposed in spaced relation, are provided through the enclosed section 16x of the pot wall for causing jets of air to be directed downwardly against the fuel vaporized in both chambers A and B of the vaporizing casing. In some installations it is desirable to make the apertures 16d which direct air into the secondary compartment B more numerous or of greater total area than the primary air intake apertures 16b for direction of jets of air into the compartment A. This is found to produce an improved pilot combustion of the small quantity of fuel consumed in pilot operation, the fuel vaporizing in chamber A being initially admixed with the downwardly directed jets of primary air and the mixture thereafter passing through the communicating passage 29a into chamber B and there, being further admixed with vaporizing fuel and a greater supply of air. The subsequent mixture then rises and is discharged laterally from the opposite upwardly diverging sides of the casing and burns in pilot setting as it discharges circumferentially in opposite directions at the top of the horizontal burner.

What is claimed is:

1. A combination pilot and vaporizing device for pot type liquid fuel burners of the structure having a substantially closed end and an opposite open flame discharge end and having a peripheral wall provided with a multiplicity of spaced air inlet passages extending therethrough, comprising a substantially closed housing the top portion of which is formed by a portion of the peripheral wall of said pot including a number of said passages and other portions of which are formed by a receptacle mounted against said top portion, said receptacle having a bottom portion for receiving fuel adapted to be connected with a source of fuel supply and having discharge passages in the side portions thereof adjacent said top portion said passages being adapted to discharge a vaporized mixture at opposite sides of said housing and in opposite directions in the interior of said pot.

2. In a horizontal, pot type liquid fuel burner, a horizontally disposed burner pot having an open end and a peripheral wall, said wall having a plurality of circumferentially and longitudinally spaced air inlet apertures therein, a vaporizing housing comprising a section of the top of said peripheral wall provided with a number of said air inlet apertures and a receptacle-like casing within said pot and secured against said section of said peripheral wall, said casing having discharge apertures adjacent the top of said pot for directing a vaporized mixture to the interior of said pot, a fuel supply conduit communicating with the lower portion of said casing and means for controlling the level of fuel at the bottom of said casing.

3. The structure set forth in claim 2 and a substantially vertical partition dividing the interior of said casing into two communicating chambers and the discharge apertures of said casing being formed in the one of said chambers remote from said fuel supply conduit.

4. A combination pilot and vaporizing device for horizontal, pot type liquid fuel burners having an open end comprising a relatively small housing adapted to be mounted within the burner and extending to the upper part of the interior thereof and spaced from the open end thereof, said housing including a bottom, end walls and a top provided with a plurality of air inlet ports spaced and distributed therein, adapted to direct jets of air downwardly, said casing having a substantially vertical partition therein defining two vaporizing and mixing chambers, means for delivering a liquid fuel to the interior of said casing into one of said chambers, said partition having an aperture in the lower portion thereof and that one of said chambers into which liquid fuel is not delivered by said delivering means having laterally extending discharge apertures through opposite sides of said peripheral wall for dis-

charging a vaporized mixture at the top of said burner pot in opposite directions.
